US00D924498S

(12) **United States Design Patent** (10) **Patent No.:** **US D924,498 S**
(45) **Date of Patent:** **** Jul. 6, 2021**

(54) **PET LITTER SCOOP**

(71) Applicant: **Hongtao Gao**, Xiangyang (CN)

(72) Inventor: **Hongtao Gao**, Xiangyang (CN)

(**) Term: **15 Years**

(21) Appl. No.: **29/772,579**

(22) Filed: **Mar. 3, 2021**

(51) LOC (13) Cl. **30-99**

(52) U.S. Cl.

USPC **D30/162**

(58) **Field of Classification Search**

USPC D30/162, 199; 273/447; D8/1, 4–11, 13, D8/14, 105, 106, 107, 300, 301, 303, 307, D8/310–313, 315–321; D34/1, 10, 28, D34/34, 35; D21/532; D29/124; D7/642, 644, 683, 685, 686, 687, 688, D7/393, 648; 119/867, 161; 294/1.3–1.5, 19.2, 19.3, 86.4, 86.11, 294/86.19, 86.42, 86.12, 86.17, 86.2, 294/86.21, 86.24, 86.26, 86.32, 87.26, 294/196–198, 210, 111, 49–58, 176, 294/180–182, 179; 132/273, 277, 283, 132/284, 128–156, 236, 252, 259–263; 15/257.1, 228, 229.2, 119.1, 119.2, 120.2, 15/104.001, 120.1, 144.3, 145; 446/424–428, 491, 330, 86; 56/400.17, 56/400.01, 400.04–400.11, 400.1, 400.14, 56/400.16, 400.21; 172/371, 373–375, 172/378, 379, 381; D32/38–40, 44, 50, D32/52, 74, 35; 16/110.1, 111.1, 421, 16/422, 429, 430, 444

CLAIM

The ornamental design for pet litter scoop, as shown and described.

DESCRIPTION

FIG. 1 is a perspective view of a pet litter scoop showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
